NEEDLE AND THIMBLE HOLDER

Robert L. Chiarizia, Saxton, Pa.

Application July 1, 1946, Serial No. 680,672

2 Claims. (Cl. 223—109)

1

The object of my invention is to provide a novel and ornamental thimble and needle holder which will retain the needles in a concealed position but which may be readily opened to permit of withdrawing or inserting a needle.

I attain the objects of my invention by the device illustrated in the accompanying drawings in which—

Figure 1 is a side elevation of the invention; and

Fig. 2 is a longitudinal median section through the same.

Like numerals designate like parts in each of the views.

Referring to the accompanying drawings, I provide a thimble 1 having an inner threaded portion 8, adapted to have a threaded engagement with the corresponding threaded portion of the cap member 2.

Mounted on the cap member 2 is an ornamental figure 3. The longitudinal channel 4 extends into the figure 3 functioning as a holder for needles. A tube 5 having a tight engagement with the base of the figure 3, projects into the cap 2 and engages the spool 6 which is extended and integral with a second spool 6a. These integral spools have a uniform and continuous channel 7 through them aligned with the tube 5 and longitudinal channel 4 in the ornamental figure

3.

When it is desired to insert needles in the holder, the thimble 1 is unscrewed at 8 from the cap 2 which is then inverted and the needles inserted in the channel 7. The thimble is then restored to its original engagement with cap member 2.

When the user wishes a needle, all he has to do is to unscrew the thimble and both the thimble and needles are always together.

What I claim is:

1. A combined thimble, needle and thread holder comprising a cup shaped cap member having external screw threads adjacent the rim thereof, a central aperture in said cap, a sleeve tightly received in said aperture and extending inwardly and outwardly of said cap, an

ornamental figure fixed on the outer portion of said sleeve and having a longitudinal channel in alignment therewith, an integral thread receiving double spool mounted on the inner portion 5 of said sleeve, said spool having a longitudinal bore therethrough in alignment with said sleeve and said channel and providing a receptacle for a plurality of needles of varying lengths and a thimble having integral screw threads for engagement with the screw threads on said cap, said thimble providing a cover for said spool and a closure for said needle receptacle.

2. A combined thimble, needle, and thread holder comprising a cap member having screw threads thereon, an aperture in said cap, a sleeve tightly received in said aperture and extending inwardly and outwardly of said cap, an ornamental figure fixed on the outer portion of said sleeve and having a longitudinal channel in alignment therewith, a thread receiving spool mounted on the inner portion of said sleeve, said spool having a longitudinal bore therethrough in alignment with said sleeve and said channel and providing a receptacle for a plurality of needles of varying lengths and a thimble having screw threads for engagement with the screw threads on said cap, said thimble providing a cover for said spool and a closure for said needle receptacle.
